METATARSAL PAD

Herchall H. Ruddick, Cincinnati, Ohio

Application January 7, 1949, Serial No. 69,781

3 Claims. (Cl. 128—166.5)

1

This invention relates to arch supports and more particularly to an arch-support pad having associated therewith simple, yet highly effective means for securing it in desired position with reference to certain portions of the foot.

An object of the invention is to provide an arch-support pad of the type adapted to be applied to the foot for providing support to the metatarsal arch formed by the five metatarsal bones, and wherein light weight retaining means are provided which engage the foot for securing the pad in position incident to all movements and motion to or thru which a foot is normally subjected.

Another object of the invention is to provide a support which is constructed whereby to flex with the foot without displacement from its pre-selected or predetermined relationship with the metatarsal arch.

A further object of the invention is to provide an arch-support having the hereinabove described characteristics which is fabricated whereby to facilitate washing, thereby enhancing foot sanitation.

Still another object of the invention is to provide a metatarsal arch-supporting pad having means for positioning it relative to the foot for effectively preventing both lateral and transverse movement of the pad relative to the foot.

Another object of the invention is to provide a pad having the hereinabove described characteristics which may be positively secured to the foot by means which make minimum contact or engagement with the foot thereby resulting in a device which is comfortable to wear and which is unlikely to bind or irritate the foot.

Further object of the invention is to provide a support which is particularly adapted to be manufactured using modern mass production techniques.

These and other objects are attained by the means described herein and as disclosed in the accompanying drawings, in which:

Fig. 1 is a plan view of a support embodying the teachings of the present invention.

Fig. 2 is an end view of the support of Fig. 1.

Fig. 3 is a side view of the support of Fig. 1.

Fig. 4 is a bottom view of a foot showing the support of Fig. 1 applied thereto.

With reference to Figs. 1, 2 and 3, it will be noted that the present device comprises a metatarsal arch-support pad 10, which is so constructed and arranged as to provide necessary and needed support to the metatarsal arch portions of a foot as formed by the five metatarsal

2

bones. In the preferred embodiment of the invention, pad 10 may be fabricated from sponge rubber, or the like, suitably shaped to properly conform with the metatarsal arch of a foot, however, I do not intend to limit my invention to pads fabricated from such material. The present invention is neither directed to nor concerned with the particular shape of pads 10, nor to the manner in which they are fabricated, so long as they are constructed in such a manner as to effectively provide support for the metatarsal arch of a foot. As illustrated in Fig. 3, the pad includes a top or upper surface 11 and a bottom or lower surface 13.

15 A foot encircling band 12 is secured to pad 10 and preferably, as disclosed in Fig. 2, said band extends under the pad to which it is suitably and permanently secured. With particular reference now to Figs. 1 and 3 and 4, it will be noted that the foot encircling band 12 engages or underlies portions of the rear third of pad 10 thereby locating said band in desired relationship with the five metatarsal bones of the foot and to the rear of the first metatarsal phalangal joint. As disclosed in Fig. 4, this relationship will locate band 12 so as to encircle the foot over the first to fifth metatarsal bones in such a manner as to effectively resist forward movement on and relative to the foot.

One or more loops 14 may be secured to band 12, as at 16 and 18, wherein each of said loops comprise interphalangeal strapping dimensioned to be located between various of the phalanges of the toes, see Fig. 4, thereby securing band 12 against rearward movement on the foot, for positively yet flexibly locating the arch-supporting pad 10 relative to the metatarsal arch of the foot.

In the preferred embodiment of the invention, band 12 and loops 14 may be fabricated from light weight, washable elastic thereby providing a support which is light weight, automatically adjustable to the contour characteristics of a foot and which may be washed, after each usage, thereby facilitating maximum sanitation.

As used herein the term metatarsus is broadly used to include or comprehend the first through fifth metatarsal bones, as the term is used in Fig. 275, page 260, of Gray's Anatomy, 32nd edition.

It should be understood that certain modifications in the structural details of the device may be made within the scope of the appended claims without departing from the spirit of the invention.

What is claimed is:

1. A support of the class described comprising a metatarsal arch supporting pad, means for positioning said pad on a human foot against lateral movement and other means for positioning said pad against longitudinal movement, said last mentioned means comprising elastic interphalangeal strapping connected with and on opposite sides of said first mentioned means.

2. A support of the class comprising a metatarsal arch supporting pad, an elastic band secured thereto dimensioned to circumscribe the foot, and a pair of elastic interphalangeal straps connected with the band on opposite sides thereof.

3. A support of the class described comprising a metatarsal arch supporting pad including top and bottom surfaces, an elastic band secured to the bottom surface thereof forming a closed loop extending around and over the top surface of the pad from which it is spaced to encircle 20 a foot at the metatarsus, and a pair of elastic,

laterally spaced, substantially U-shaped interphalangeal straps extending in the same direction from said band, one end of each strap secured to the band adjacent the bottom surface of the pad, the opposite end of each strap secured to portions of the band which extend over the top surface of the pad.
